HOLDER FOR AN ELECTRIC TOOTHBRUSH

William J. Cook, Trumbull, Conn., assignor to
General Electric Company

Filed Sept. 23, 1970, Ser. No. 25,168

Term of patent 14 years

Int. Cl. D4—02

U.S. Cl. D4—16

Fig. 1.

Fig. 2.

Fig. 3.

Fig. 4.

Fig. 5.

Fig. 6.

Fig. 7.

FIG. 1 is a perspective view of a holder for an electric toothbrush embodying my new design;
 FIG. 2 is a front elevational view;
 FIG. 3 is a left side elevational view;
 FIG. 4 is a top plan view;
 FIG. 5 is a bottom plan view;
 FIG. 6 is a rear elevational view; and
 FIG. 7 is a right side elevational view.

I claim:

The ornamental design for a holder for an electric toothbrush, substantially as shown.
